US00D830341S

(12) **United States Design Patent** (10) Patent No.: **US D830,341 S**
(45) Date of Patent: **** Oct. 9, 2018**

(54) **WEARABLE SPEAKER**

(71) Applicant: **SONY CORPORATION**, Tokyo (JP)

(72) Inventor: **Ryota Yokozeki**, Kanagawa (JP)

(73) Assignee: **SONY CORPORATION**, Tokyo (JP)

(**) Term: **15 Years**

(21) Appl. No.: **29/597,414**

(22) Filed: **Mar. 16, 2017**

(30) **Foreign Application Priority Data**

Jan. 20, 2017 (JP) D2017-000812

(51) **LOC (11) Cl.** **14-01**

(52) **U.S. Cl.**

USPC **D14/210**; D14/205

(58) **Field of Classification Search**

USPC D14/168, 188, 194, 195, 196, 204, 210, D14/211, 212, 213, 214, 215, 216, 197, D14/198, 223, 205, 206; D24/174; 181/129, 130, 135; 128/864, 866, 867; 381/381, 380

(57) **CLAIM**

The ornamental design for a wearable speaker, as shown and described.

DESCRIPTION

FIG. 1 is a perspective view of a wearable speaker showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines illustrating unclaimed portions of the wearable speaker form no part of the claimed design.

1 Claim, 7 Drawing Sheets
